US0D1033185S

(12) **United States Design Patent** (10) **Patent No.:** **US D1,033,185 S**
(45) **Date of Patent:** **** Jul. 2, 2024**

(54) **WINE BOTTLE OPENER**

(71) Applicant: **Ningbo Chuangxin Jump E-Commerce Co., Ltd., Zhejiang (CN)**

(72) Inventor: **Han Ding, Zhejiang (CN)**

(**) Term: **15 Years**

(21) Appl. No.: **29/919,683**

(22) Filed: **Dec. 5, 2023**

(51) LOC (14) Cl. **07-06**

(52) U.S. Cl.

USPC **D8/38**

(57) **CLAIM**

The ornamental design for a wine bottle opener, as shown and described.

DESCRIPTION

FIG. 1 is a perspective view of a wine bottle opener showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the wine bottle opener is in use.

The broken lines in the drawings illustrate the portions of the wine bottle opener that form no part of the claimed design.

1 Claim, 9 Drawing Sheets
